UNITED STATES PATENT OFFICE.

ABRAHAM L. ADAMS, OF BRIDGEPORT, CONNECTICUT.

KNOCKDOWN FLUME.

SPECIFICATION forming part of Letters Patent No. 658,332, dated September 25, 1900.

Application filed February 1, 1900. Serial No. 3,636. (No model.)

To all whom it may concern:

Be it known that I, ABRAHAM L. ADAMS, a citizen of the United States, and a resident of Bridgeport, in the county of Fairfield and 5 State of Connecticut, have invented certain new and useful Improvements in Knockdown Flumes, of which the following is a specification.

My invention relates to a knockdown flume 10 for holding and conveying water, the detail construction of which will be fully set forth and described in the following specification.

To enable others to understand my invention, reference is had to the accompanying 15 drawings, in which—

Figure 1 represents a broken side elevation of my improved knockdown flume, whose locking device consists of a series of skeleton frames or binders embracing the four 20 sides of the flume, said binders being shown in a vertical position or unlocked. Fig. 2 is an end elevation of Fig. 1. Fig. 3 is a broken side elevation of the flume locked. Fig. 4 is an end elevation of Fig. 3. Fig. 5 is a broken 25 side elevation of the flume, showing the binders locked and also the means whereby the flume may be extended indefinitely. Fig. 6 is a broken section of the upper side of an open flume and one of its binders. Fig. 7 is an end elevation of the flume and a modification of the binder. Fig. 8 is an end elevation of one of the flume-boards. Fig. 9 is a 30 broken side elevation of the flume, showing the corners reinforced by angle-strips, the whole bound together by means of a metal 35 strap and wedges. Fig. 10 is an end view of the construction shown at Fig. 9. Fig. 11 is a broken side elevation of the flume without the reinforce angle-strips. Fig. 12 is an end 40 view of the construction shown at Fig. 11. Fig. 13 is an end elevation of the flume having only three sides.

The construction and operation are as follows:

45 The sides of the flume are composed of the boards 1, (see Fig. 8,) having the beveled edges 1^a, which beveled edges are the meeting faces of the sides of the flume when assembled.

50 As the object of my invention is to construct a flume that can be readily and quickly put together or taken apart without employ-

ing nails, screws, or other common mode of fastening, it is necessary to apply a binder around the exterior. In Figs. 1, 2, 3, 4, 5, 55 5 and 6 are shown binders consisting of a skeleton frame which loosely embraces the exterior of the flume when in a vertical position, as shown at Figs. 1, 2, and 6; but when canted, as shown at Figs. 3, 4, and 5, the top and bottom rails 2 and 3 will crowd against the top and floor of the flume. Under this pressure the beveled edges 1^a of such top and bottom acting against the corresponding beveled edges of the sides will force such sides hard 60 65 against the side rails 4 and, 5 of the binder-frames, as shown at Fig. 4, thus firmly holding the flume together without the use of nails or screws. In taking the flume down all that is necessary is simply to force the 70 binder-frames into a vertical position, and thus release their grip on the top and floor of the flume. The flume can be extended to an indefinite length by simply abutting the end of another board against the end 1^b, as shown 75 at Fig. 5. 6, Fig. 6, is one of a series of strips, also provided with beveled edges to rest against the beveled edges of the side pieces or boards when the top is removed, so as to make an open flume, if desired. These 80 narrow strips are placed directly under the binders and operate in the same way to spread the side boards of the flume.

In Fig. 7 is shown a modification of the before-mentioned binder-frames. In this construction the binders are not canted; but the same effect is produced by means of the key or wedge 7 acting against the tapered side 4 of the binder-frame and one side of the flume.

Where there is great internal pressure required—as, for instance, in hydraulic mining—I prefer to reinforce the corners of the flume by means of the angle-strips 8, Figs. 9 and 10. For binders either the skeleton-frames shown at Fig. 1 or the metal strips or 95 bands 9, Figs. 9 and 10, can be used. In the latter case the bands are held in position by means of the nails 11, driven into the longitudinal wooden strip 12, lying against one side of the flume opposite the keys 10. This continuous metal binder being thus secured at every turn about the flume virtually converts said binder into separate individual bands, so that the tightening effect of each wedge or 100

key is only exerted on that particular metal band with which it is engaged. While there is an advantage in using the long strip in the first winding, the wedges will exert a better 5 tightening effect by fastening the bands to the strip 12 at each revolution.

In Figs. 11 and 12 are shown the use of metal bands and keys without the reinforce angle-strips. In some cases it might be desirable 10 to make a tank-like structure with one or both ends closed, as shown at Fig. 12, in which case the end 13 is simply let into the grooves 14, formed on the inside faces of the sides of the flume.

15 The novel feature of beveling the meeting faces of the top, floor, and side walls of the flume and applying an outward pressure on opposite sides, as indicated by arrows *a* and *b*, will, as before mentioned, produce a resultant 20 force in the direction as indicated by the arrows *c d*. This peculiar construction is the main feature or gist of my invention, and, as before stated, is applicable to any shape of flume to which this principle will apply.

25 Having thus described my invention, what I claim as new, and desire to secure by Letters Patent, is—

1. The herein-described improvement in a knockdown flume having three or more sides 30 each of said sides provided with a beveled meeting face, combined with a binder adapted to envelop all of said sides, for the purpose set forth.

2. The herein-described improvement in a 35 knockdown flume having three or more sides

provided with beveled meeting faces, combined with a binder adapted to envelop all of said sides, means whereby force is applied to one or more of said sides to produce a resultant force at an angle to the initial force so as 40 to crowd the remaining sides of the flume hard against the binder and thus firmly lock the whole structure together, for the purpose set forth.

3. The herein-described improvement in 45 knockdown flumes having three or more sides provided with beveled meeting faces, angle-strips adapted to reinforce the corners of said flume, a binder adapted to embrace said angle-strips, means substantially as shown for locking 50 the sides of said flume, for the purpose set forth.

4. The herein-described improvement in knockdown flumes having three or more sides provided with beveled meeting faces, combined with a metal-strap binder adapted to be spirally wound around said sides, a horizontal wooden strip adapted to rest against one side of the flume, said metal-strap binder adapted to be secured to such horizontal strip 55 60 at every turn about the flume, for the purpose as described and set forth.

Signed at Bridgeport, in the county of Fairfield and State of Connecticut, this 26th day of January, A. D. 1900.

ABRAHAM L. ADAMS.
